HYDRAULIC PUMPING UNIT

James W. McQuaid, Overton, Tex.

Application November 22, 1933, Serial No. 699,275

1 Claim. (Cl. 60—54.5)

This invention relates to a hydraulic pumping unit and has for the primary object the provision of a device of the above stated character whereby a series of well pumps may be successfully and 5 economically operated through hydraulic pump jacks operated from a single hydraulic unit or pump driven by a power source.

With these and other objects in view this invention consists in certain novel features of construction, combination and arrangement of parts to be hereinafter more fully described and claimed. For a complete understanding of my invention, reference is to be had to the following description and accompanying drawings, in which

15 Figure 1 is a top plan view illustrating a hydraulic pumping unit constructed in accordance with my invention.

Figure 2 is a vertical sectional view illustrating the hydraulic unit or pump.

20 Figure 3 is a side elevation illustrating the same.

Figure 4 is a sectional view taken on the line 4—4 of Figure 2.

Figure 5 is a fragmentary side elevation partly in section illustrating a fluid recharging pump.

25 Figure 6 is a front elevation partly in section illustrating the same.

Figure 7 is a horizontal sectional view showing the manifold connection between the cylinders of the recharging pump and its connection with the fluid pipes of the hydraulic unit.

30 Figure 8 is a front elevation illustrating one of the hydraulic jacks.

Figure 9 is a side elevation illustrating the same.

Figure 10 is a sectional view taken on the line 35 10—10 of Figure 9.

Figure 11 is a fragmentary sectional view illustrating a cylinder and piston of the hydraulic jack and a safety device applied to the cylinder.

Referring in detail to the drawings, the numeral 40 1 indicates a hydraulic unit or device for actuating a series or plurality of hydraulic pump jacks 2 and the hydraulic unit 1 consists of a base 3 suitably mounted on a foundation 4 and formed integrally with a crank case 5 of cylindrical 45 formation having removable end plates which rotatably support a power shaft 6 carrying at one end a pulley 7 or any other suitable medium for connecting the power shaft to a power source (not shown). Extending radially from the crank case 5 are cylinders 8 which are bolted or otherwise secured to the crank case and each is equipped with a piston 9 and the stem of the latter extends outwardly through the outer end of the cylinder by way of a packing gland 10. The inner ends of 55 the cylinders have ports 11 connected to pipes 12

which are in turn connected to the hydraulic jacks 2. The stems of the pistons have heads 13 to which are journaled the outer ends of connecting rods 14. The connecting rods extend through slots 15 into the crank case and are pivotally connected to an anti-friction medium 16 forming a part of an eccentric 18. The eccentric is secured to the power shaft 6. The anti-friction medium is in the form of inner and outer races having 5 balls interposed between said races and the inner race is suitably connected to the periphery of the eccentric and the outer race has pivoted thereto the inner ends of the connecting rods. The rotation of the power shaft 6 will impart reciprocation to the pistons through the eccentric 18 and 15 the connecting rods. The cylinders and pipes are filled with a fluid and this fluid is caused by the reciprocation of the pistons to move back and forth through the pipes 12 for the purpose of operating the hydraulic jacks which will be hereinafter more fully described.

20 Each hydraulic jack consists of a cylinder 20 removably secured to the top plate 21 of a support 22 and the latter besides consisting of the plate 21 also includes legs bolted or otherwise secured to a base plate 23 mounted upon a foundation 24 located at the mouth of the well and through which the ordinary pump rigging 25 operates. A piston 26 is reciprocally mounted in the cylinder 20 and the stem thereof extends 25 through the upper end of said cylinder by way of a packing gland 27 and carries a head 28 to which are journaled connecting rods 29, the lower ends of which are secured to a beam 30 suitably secured to the pump rigging 25 so that upon reciprocation of the piston 26, a corresponding movement will be imparted to the pump rigging. The cylinder 20 has a port 31 to which one of the pipes 12 is connected. When the fluid in one of the cylinders of the unit 1 is displaced therefrom, said fluid will be forced into the cylinder 20 of the pump jack connected to the respective cylinder of said unit which will cause a movement of the piston of the pump jack in an upward direction which carries therewith the pump rigging in an upward direction. Upon the movement of the piston of the unit 1 outwardly of its respective cylinder the piston of the pump jack is permitted to move downwardly in its respective cylinder under the weight of the well rigging 30 35 40 45 50 55 connected thereto.

A reservoir 32 is mounted on the crank case 5 of unit 1 and has a feed pipe 33 connected thereto which is in turn connected to a distributing head 34 and the latter is carried upon and 55

connected to a manifold 35, and the latter connects pump cylinders 36. The pump cylinders are located at opposite sides of one of the cylinders 8 of the unit 1 and have reciprocally mounted therein pistons 37, the stems of which are connected to the head 13 of the piston of the respective cylinder 8 of the unit 1. The distributing head 34 has a pipe 38 connected thereto which is in turn connected to a manifold 39 provided with branches 40, which are connected to the pipes 12 and said branches have cut-off valves 41 therein. A check valve 40' is located in the pipe 38 to prevent back pressure in the manifold 39 from entering the distributing head 34. The head 34 is equipped with check valves 42 and 43. The check valve 42 permits fluid from the reservoir 32 to be drawn into the manifold 35 by the pump while the check valve 43 permits said fluid to be exhausted from the manifold 35 to the manifold 39 by way of the pipe 38 and into the pipes 12 when the valves 41 are opened. With this arrangement the hydraulic system can be at any time replenished with fluid.

A suitable bypass means 46' may be provided 25 between the reservoir 32 and the manifold 35 whereby the fluid may be bypassed back to the reservoir when the system or the pipes 12 thereof are properly filled with fluid and the valves 41 closed.

30 Each hydraulic jack or the cylinder 20 thereof is provided with a port 44 to which a check valve 45 is connected and the latter is connected to a pipe 46 providing a return to the reservoir 32.

The port 44 and the check valve 45 provide the hydraulic jack with a safety device, that is, should an excessive amount of fluid be placed in the system and there would be danger of forcing the piston of the hydraulic jack too far up in its respective cylinder, the piston will uncover the port 44 before reaching a point in the cylinder that would endanger the construction of the head of the cylinder by the piston so that the excessive amount of fluid may pass to the pipe 10 5 46 and return to the reservoir.

Having described the invention, I claim:

A hydraulic transmission system comprising a series of hydraulically driven elements, pipes connected to said elements, hydraulic cylinders 15 grouped radially with respect to one another and each connected with one of said pipes, pistons operating in said cylinders, a common crank case supporting said cylinders, a power shaft journaled in said crank case, means between the 20 pistons and the power shaft to reciprocate said pistons, a supply reservoir mounted on the crank case, fluid release means for said driven elements and connected to said reservoir, pumps mounted on one of said first-named cylinders and actuated by the piston of the latter, a manifold means connecting said pumps to the reservoir and to the pipes, check valves for said manifold means, and a manually controlled bypass means connected to the manifold means and to the fluid release 25 means adjacent the latter's connection to the reservoir.

JAMES W. MCQUAID.
